UNITED STATES PATENT OFFICE.

OTIS A. MYGATT, OF NEW YORK, N. Y.

DESIGN FOR A GLASS REFLECTOR.

No. 37,984.

Specification for Design.

Patented May 1, 1906.

Application filed July 14, 1905. Serial No. 269,729. Term of patent 14 years.

To all whom it may concern:

Be it known that I, OTIS A. MYGATT, a citizen of the United States, residing at New York, in the county of New York and State of New York, have invented a certain new, original, and ornamental Design for Prismatic-Glass Reflectors, of which the following is a specification, reference being had therein to the accompanying drawings, forming part thereof.

Figure 1 is a side elevation of a reflector embodying my design. Fig. 2 is a perspective view from a plane or point somewhat below the reflector.

The reflector is of the form shown in the

drawings, and its body is externally covered with reflecting prisms which are indicated by lines in the drawings. The prisms are visible on the interior of the reflector, as attempted to be indicated by dotted lines, Fig. 2.

I claim—

The ornamental design for a glass reflector having its body of the form shown, and covered with prisms visible on the outside and inside of the reflector, as described.

OTIS A. MYGATT.
